UNITED STATES PATENT OFFICE.

THOMAS H. SMITH, OF DECATUR, NEBRASKA.

COAL-LOADING DEVICE.

1,122,546.

Specification of Letters Patent. Patented Dec. 29, 1914.

Application filed February 24, 1914. Serial No. 820,639.

To all whom it may concern:

Be it known that I, THOMAS H. SMITH, a citizen of the United States, residing at Decatur, in the county of Burt and State of Nebraska, have invented certain new and useful Improvements in Coal-Loading Devices, of which the following is a specification, reference being had therein to the accompanying drawing.

10 This invention relates to the subject of coaling ships, and the principal object of the same is to provide a novel coal pier which is equipped with simple means for rapidly and economically supplying coal to ships.

The invention contemplates the employment of a pier, or piers arranged to provide a dock or slip in which the ship to be coaled is moored, the piers being provided with 20 coal pockets which are supplied with coal from overhead cars, said pockets being provided with outlets from which discharge spouts project, said spouts being adapted to be placed in communication with the passages that lead to the bunkers of the ship so 25 that the coal can be quickly transferred from the said pockets to the said bunkers.

In carrying out the objects of the invention generally stated above, it will be understood of course, that changes in details and structural arrangements may be resorted to, one preferred and practical embodiment of which is shown in the accompanying drawings, wherein:—

35 Figure 1 is a fragmentary top plan view of the improved coal handling pier, showing a ship receiving coal therefrom. Fig. 2 is a transverse vertical sectional view taken on the line 2—2, Fig. 1. Fig. 3 is a horizontal sectional view of a portion of one of the discharge spouts. Fig. 4 is a fragmentary vertical sectional view of the improved pier showing the outlet of one of the coal pockets therein. Fig. 5 is an end view 40 of one of the discharge spouts.

Referring to the accompanying drawings by numerals it will be seen that the improved coal piers 8 are preferably formed of plastic or other strong fireproof mate-

rial, two of the piers being shown in the 50 accompanying drawings and arranged in spaced parallel relation to provide a dock or slip 9 between them which is sufficiently large to permit a battleship or the like 10 to be moored therein so that each pier can 55 deliver coal to said ship in a rapid, economical and practically dustless manner. The piers 8 are provided with coal pockets 8^a having inclined bottoms 8^b with which the discharge outlets 11 communicate. The said 60 outlets 11 are preferably on the same incline and are continuations of the bottoms of said pockets. The rear walls 12 of said pockets are inclined and terminate in beveled ledges 13 which prevent coal packing against said 65 rear walls and overhang the outlets of recesses 14 which extend into said rear walls. Said recesses 14 are in alinement with the outlets 11. Vertical partitions 15 are arranged in the pockets 8^a between adjacent 70 outlets 11, said partitions being preferably V-shaped so that their beveled sides will prevent coal from packing between said outlets and their flat front surface can be fastened in flush contact with the inner surface 75 of the front walls of said pockets 8^a. The pockets 8^a are open at their tops and supporting beams 16 extend transversely across the same. Rails 17 are carried by said beams 16 for the dumping cars 18 so that 80 said cars can be moved to desired positions over said pockets and discharge their contents directly to the pockets.

Laterally projecting brackets 19 are carried by the outer vertical walls or sides of 85 the piers 8 below the outlets 11, said brackets carrying supporting bars 20. Suspending braces 21 are employed for connecting said bars 20 to the outer walls of the piers. The bottoms of the pockets 8^a are provided with 90 supporting frames or runways 22 that extend into the recesses 14 and also into the outlets 11. Said runways have sections 23 hinged to their outer ends which rest on the bars 20 and project well beyond the 95 same. Said sections 23 have lugs 24 projecting laterally from their outer portions and to which cables 25 are fastened. The

cables 25 extend from winding drums 26 carried by shafts 27 arranged at the upper portions of the piers 8 and which may be rotated by any suitable power to rotate the 5 same so that the drums 26 will adjust the cables 25 to raise or lower the sections 23. The sections 23 preferably have their bases 28 closed so that when raised to a vertical position they will lie in contact with the 10 piers and seal the outlets 11 so that no coal will escape from said outlets.

Discharge spouts 29 are provided for each outlet, said spouts being open at their ends and closed at their tops, sides and bottoms. Said spouts are slideable over the 15 runways 22 on the anti-friction rollers 30 carried by said runways. Internally, the spouts 29 are provided with spaced parallel partitions 31 which are arranged to provide 20 tortuous passages 32 through said spouts so that the passage of coal thereto will be comparatively slow. The spouts 29 are projected or retracted by means of the cables 33 which 25 connect the outer ends of the spouts with drums 34 carried by shafts 35 located in recesses 36 formed in the outer walls of the piers above the outlets 11. The shafts 35 are rotated by means of the belts or chains 37 which connect with the power shafts 38 30 at the upper portions of the piers. When retracted the spouts 29 lie within the pockets 8^a with their inner ends extending into the rear recesses 14 and their outer ends within the outlets 11 so that they will not 35 interfere with the pivotal movements of the runway sections 23.

In Figs. 1 and 2 the invention has been shown in practical use and by reference thereto it will be seen that the spouts can be 40 adjusted so that their outer ends will project through the hatchways of the passages 39 which lead to the bunkers 40 of the ship, and, as clearly shown in Fig. 2, said hatchways may be provided with doors 41 that 45 can be closed over the outlet ends of said spouts to prevent the escape of dust.

It will be understood that the spouts being adjustable, they can be readily positioned relative to the vessel to be loaded and 50 being only open at their ends the coal will be delivered from the piers to the bunkers of the vessel with the escape of little, if any dust.

While in the foregoing description particular stress has been laid on the invention 55 for use in connection with supplying coal to ships, it is to be understood that the same is but one of the many uses of the same. It will be readily apparent that the invention 60 is of especial value in handling grain, oil, or other cargoes that are to be delivered to vessels in bulk.

What I claim as my invention is:—

1. A loading device comprising a pier 65 provided with a pocket, said pocket pro-

vided with an outlet and a rear recess which are in alignment, a runway in said recess and extending through said outlet, said runway having an outer section hinged thereto that projects beyond the pier, means for adjusting 70 said hinged section so that the same will seal said outlet, a discharge spout slideable on said runway, and means for projecting and retracting said spout.

2. A loading device comprising a storage 75 structure provided with a pocket, said pocket having an incline bottom and regularly spaced inclined outlets, said pocket being provided with inclined rear recesses which are in alignment with said outlets, 80 runways in said recesses and extending through said outlets, end sections hinged to said runways, means for adjusting said sections, discharge spouts slideable in said pocket on said runways and adapted to be 85 projected beyond said outlets or retracted within the rear recesses, and means for projecting and retracting said spouts.

3. A loading device comprising a pier provided with a pocket, said pocket being 90 provided with outlets, runways projecting through said outlets, means for adjusting the outer portions of said runways, discharge spouts carried by said runways, and means for adjusting said spouts.

4. A loading device comprising a pier provided with a pocket, said pocket being provided with discharge outlets, brackets carried by said pier below said outlets, a supporting bar carried by said brackets, 100 runways projecting through said outlets and having their outer ends resting on said bar, and discharge spouts carried by said runways.

5. A loading device comprising a fire- 105 proof structure provided with a pocket, the bottom of said pocket being inclined, said pocket having front outlets and rear recesses, said outlets and recesses being in alignment, means carried by the rear wall 110 of said pocket and overhanging the recesses to prevent material packing therein, means carried by the inner surface of the outer wall of said pocket and arranged between said outlets for preventing material packing 115 between said outlets, and discharge means slideable in said outlets and recesses.

6. A loading device comprising a storage 120 structure provided with a pocket, said pocket provided with discharge outlets, runways in said pockets and projecting through said outlets, said runways having outer sections hinged thereto, anti-friction rollers carried by said runways, a shaft carried by 125 said structure, drums on said shaft, cable connections between said drums and said hinged sections for adjusting the same, discharge spouts slideable on said runways, a shaft carried by the structure, drums on said last mentioned shaft, and cable con- 130

nections between the last mentioned drums and said spouts for projecting and retracting said spouts.

7. A loading device comprising a pier 5 provided with a pocket, said pocket being provided with outlets, runways projecting through said outlets and provided with adjustable outer ends, means for adjusting the outer ends of said runways, discharge

spouts adjustable on said runways through 10 said outlets, and means for adjusting said spouts.

In testimony whereof I hereunto affix my signature in presence of two witnesses.

THOMAS H. SMITH.
